UNITED STATES PATENT OFFICE.

WILLIAM W. KEYS, OF LANCASTER, OHIO.

JAR-TOP.

1,201,741.

Specification of Letters Patent. Patented Oct. 17, 1916.

Application filed July 12, 1916. Serial No. 108,886.

To all whom it may concern:

Be it known that I, WILLIAM W. KEYS, a citizen of the United States, residing at Lancaster, in the county of Fairfield and State of Ohio, have invented a new and useful Jar-Top, of which the following is a specification.

The present invention relates to jar tops, and aims to provide a novel and improved 10 yet simple, inexpensive, convenient and efficient closure means for fruit jars, cans, and the like.

With the foregoing and other objects in view which will appear as the description 15 proceeds, the invention resides in the combination and arrangement of parts and in the details of construction hereinafter described and claimed, it being understood that changes in the precise embodiment of 20 the invention herein disclosed can be made within the scope of what is claimed without departing from the spirit of the invention.

The invention is illustrated in the accompanying drawing, wherein:

25 Fig. 1 is a side elevation of the jar top. Fig. 2 is a section on the line 2—2 of Fig. 1.

The jar or can 1 illustrated is provided with a neck 2 having the head or outstanding rim 3, and the device for clamping the 30 cover on the neck embodies a yoke 4 bent from a bar of relatively stiff metal, and having the limbs 5 adapted to be disposed at diametrically opposite points of the neck and provided at their lower ends with in- 35 turned lips or flanges 6 to engage under the rim 3. The yoke 4 is provided between its ends with an upstanding relatively long doubled or inverted U-shaped guide 7 in which a square nut 8 is fitted for vertical 40 sliding movement, said nut being constrained from rotating by the guide 7, since opposite straight sides of the nut bear against the limbs or side portions of said guide. A bolt or spindle 9 is slidable 45 through the upper closed end of the guide, and has its lower terminal threaded through the nut 8, and the upper protruding end

of the spindle or bolt 9 has a thumb and finger piece 10. A coiled wire expansion spring 11 is confined between the upper 50 closed end of the guide and the nut 8 and is disposed snugly within said guide, and the lower end of the bolt 9 is adapted to contact with or bear upon the central portion of the cover 12 of the jar.

When the cover 12 is placed upon the jar, the yoke 4 can be readily moved laterally into place, as seen in Fig. 1, and then by rotating the bolt 9 in the proper direction, with the lower end of said bolt bearing upon 55 the cover 12, the nut 8 will be forcibly moved upwardly away from the cover 12, thereby compressing the spring 11, which will force the bolt 9 downwardly by spring tension to hold the cover 12 in place. The 60 cover 12 is thus yieldably held in place, and can yield, if necessary, to avoid the breaking of the jar or cover, but at the same time, the spring 11 in being brought under the desired tension, will hold the cover closed 65 to provide a tight joint, which will be sufficient to prevent leakage under the cover.

Having thus described the invention, what is claimed as new is:

A device of the character described embodying a yoke having means at its ends for engaging under the rim of a jar and having a relatively long upstanding doubled guide between its ends, a bolt slidable through the upper closed end of said guide 75 and adapted to bear upon a jar cover, a nut slidable vertically within said guide and prevented from rotating thereby, the bolt being threaded through said nut, and a coiled wire expansion spring within the 80 guide confined between the upper closed end thereof and the nut.

In testimony that I claim the foregoing as my own, I have hereto affixed my signature in the presence of two witnesses.

WILLIAM W. KEYS.

Witnesses:

C. E. RUBLE,

W. E. ROWLES.
